UNITED STATES PATENT OFFICE.

WILLIS G. FAWCETT, OF SALEM, OHIO.

DESIGN FOR A COMBINED HAT AND CLOTHES HOOK.

50,217.

Specification for Design.

Patented Jan. 23, 1917.

Application filed September 12, 1914. Serial No. 861,474. Term of patent 3½ years.

To all whom it may concern:

Be it known that I, WILLIS G. FAWCETT, a citizen of the United States, residing at Salem, in the county of Columbiana and State of Ohio, have invented a new, original, and ornamental Design for a Combined Hat and Clothes Hook, of which the following is a specification, reference being had to the accompanying drawing, forming part thereof.

In the drawing: Figure 1 is a front elevation of my combined hat and clothes hook. Fig. 2 is a side elevation of the same.

I claim:

The ornamental design for a combined hat and clothes hook, substantially as shown.

WILLIS G. FAWCETT.
